UNITED STATES PATENT OFFICE.

WILLIAM E. JACQUES, OF LAKELAND, FLORIDA.

SPARK-PLUG.

1,318,761.

Specification of Letters Patent. Patented Oct. 14, 1919.

Application filed April 21, 1917. Serial No. 163,732.

To all whom it may concern:

Be it known that I, WILLIAM E. JACQUES, a citizen of the United States, and a resident of Lakeland, in the county of Polk and State of Florida, have invented a certain new and useful Improvement in Spark-Plugs, of which the following is a specification.

The present invention relates to internal combustion engines, and has particular reference to a novel construction of spark plug adapted for application to the same.

An object of the present invention is to provide a simplified and durable construction of spark plug which may be economically produced and sold at a relatively low cost.

Another object of the present invention is to provide a spark plug having a single electrode adapted to coöperate with the adjacent wall of the cylinder of the engine when the spark plug is in position to form the spark gap, and the provision of a peculiar mounting for the single electrode and its stem for varying the distance between the electrode and the wall of the cylinder for varying the spark gap.

The invention further aims at the provision of a spark plug comprising relatively few parts which are of novel construction, and assembled in a novel manner.

The above, and various other objects and advantages of this invention will be in part described, and in part understood, from the following detailed description of the present preferred embodiment, the same being illustrated in the accompanying drawing wherein:

Figure 1 is a longitudinal section through a spark plug constructed according to the present invention and as applied to the wall or head of a cylinder, the latter being shown fragmentarily and in section.

Fig. 2 is a side elevation of the spark plug.

Fig. 3 is an inner end view of the same.

Fig. 4 is an outer end view of the plug.

Fig. 5 is a transverse section taken through the plug substantially on the line 5—5 of Fig. 2, looking in the direction of the arrows.

Referring to this drawing, A designates the wall or head of a cylinder which may be of any suitable construction, and which is provided in the usual manner with a

threaded bore B adapted to receive a spark plug.

The spark plug comprises a barrel 10 which may be in the form of an externally threaded casting provided upon its outer end with an outstanding angularly faced flange 11 adapted to receive a wrench or the like for screwing the barrel 10 into and out of the bore B of the cylinder wall A. The barrel 10 is provided with an axial opening which preferably tapers from its inner to its outer end, and is adapted to receive therein a corresponding tapered core 12 preferably formed from insulating material, such as porcelain or the like. The core 12 is packed or sealed in the barrel 10, by the provision of a filler 13 of cement or the like adapted to hold the core 12 rigidly in the body 10 and prevent the passage of gas upwardly through the plug.

The core 12 is provided with a longitudinal opening therethrough eccentric to the central axis of the core, and through which is passed a stem 14 formed of a single length of wire of the desired gage adapted to fit tightly in the core 12. The core 12 may be molded and compressed about the stem 14 in the manufacture of the plug, and the lower end of the stem 14 is provided with oppositely extending lugs or projections 15 formed by swaging or pressing portions of the stem body outwardly at the lower end thereof. The lower extremity of the stem 14, beyond the projections 15, is bent laterally at substantially right angles to the axis 90 of the stem 14 to provide an electrode 16 the extremity of which approaches the adjacent wall of the bore or cylinder B when the plug is in position. By virtue of the eccentric mounting of the stem 14 in the core 12, by turning the stem 14 the electrode 16 may be advanced toward and from the adjacent wall of the cylinder to vary the size of the spark gap between the wall and the electrode. While the stem 14 may be turned 95 by a suitable tool, it is tightly clamped in the core 12 to prevent egress of gases through the plug. The outer end of the stem 14 is provided with a relatively flat broad head 17 which is apertured for the 105 reception of the terminal portion of a wire C forming one side of the high tension circuit. The head 17, and the outer end of the stem 14 are of sufficient length beyond the outer end of the core 12 to receive a U- 110

shaped spring clip 18 thereon beneath the wire C, the outer portion of the clip 18 engaging the wire C and binding it in the opening through the head 17. The clip 18 is in the form of a strip of spring metal which is overturned upon itself and provided with elongated openings in its opposite arms which register and through which may freely extend the head 17 and the outer 10 end of the stem 14. The stem 14 is thus yieldingly held in the core 12 by the clip 18, and the wire C yieldingly held in the head 17 by the clip. Preferably, the outer end of the core 12 is rounded or convexed 15 to conform to the concaved flaring side of the clip 18 to form a frictional bearing surface for the clip and prevent the turning thereof on the core, and the elongated openings in the arms of the clip are of a width 20 less than the width of the head 17 to hold the latter from turning in the clip. The clip 18 therefore holds the stem 14 yieldingly in adjusted position to prevent the accidental turning of the stem by the vibration 25 of the engine when running. A gasket 19, in the form of a packing ring, surrounds the barrel when immediately beneath the flange 11 and is adapted to seat against the outer face of the cylinder wall 30 A to seal the barrel 10 therein when the plug is in position.

It may be thus noted that the spark plug of this invention may be economically constructed from relatively cheap material, and 35 that it comprises relatively few parts. It is also provided with a novel arrangement or interfitting of the parts to secure the desired adjustment without the bending or the breaking of the electrode 16, the adjustment 40 being a minute one so as to obtain a spark gap of the desired dimension. The stem and the electrode are formed from a single length of relatively small wire which is swaged or stamped out to form 45 the shoulder or abutment at its lower end, and the core 12 may be molded about the wire after the shoulder is formed, fits the wire snugly and practically seals the

wire in the core. This frictional contact between the core and the stem or wire 14 is 50 such as to yieldingly hold the stem in adjusted position, and coöperates with the spring clip 18 in retaining the electrode 16 at the desired radial adjustment with respect to the axis of the stem. By utilizing 55 the side wall of the cylinder as one side of the circuit, or an electrode, the number of parts of the plug are considerably reduced, and a relatively strong durable and economically constructed plug is produced. 60

It is of course understood that various changes and modifications may be made in the details of construction and in the selection of materials of the above-specifically described spark plug without departing from 65 the spirit of the invention, and being restricted only by the scope of the following claims.

I claim:—

1. In a spark plug, the combination of a 70 barrel adapted to be screwed in a cylinder wall and provided with an outwardly tapering axial opening, a correspondingly tapered core sealed in said opening, a stem extending longitudinally and eccentrically through 75 said core, and an electrode projecting laterally through the inner end of the cylinder and approaching said cylinder wall, said stem being adapted to be turned in said core to vary the size of the spark gap between 80 said electrode and said cylinder wall.

2. In a spark plug, the combination of an externally threaded barrel adapted for engagement in a cylinder wall, a tapering core fitting in said barrel, a seal between said 85 core and said barrel to retain the core therein, and an eccentrically mounted stem projecting longitudinally through the core and provided with a laterally turned inner end forming an electrode adapted to approach 90 the cylinder wall when the plug is in position, said stem being adapted to be rotated to move the extremity of the electrode toward and from the cylinder wall.

WILLIAM E. JACQUES.
